United States Patent [19]

Koch

[11] Des. 243,594

[45]  Mar. 8, 1977

[54] SELF-PROPELLED HANG GLIDER CARRIAGE

[76] Inventor: Jeffrey F. Koch, P.O. Box 453, Petaluma, Calif. 94952

[] Term: 14 Years

[21] Appl. No.: 619,667

[22] Filed: Oct. 6, 1975

[51] Int. Cl. .... D12—07

[52] U.S. Cl. D12/81

[58] Field of Search D12/81, 71; 244/16, 244/13

[56] References Cited

U.S. PATENT DOCUMENTS

1,735,308 11/1929 Worrell 244/13

3,204,368	9/1965	Effinger, Jr. et al.	244/16 X
3,813,060	5/1974	Mochizuki	244/13
D. 233,426	10/1974	Jensen et al.	D12/71

Primary Examiner—Alan P. Douglas

Attorney, Agent, or Firm—Melvin R. Stidham

[57]

CLAIM

The ornamental design for a self-propelled hang glider carriage, as shown.

DESCRIPTION

FIG. 1 is a view in perspective from the front of the self-propelled hang glider carriage of my new design; and

FIG. 2 is a view in perspective from the rear thereof.